UNITED STATES PATENT OFFICE

RUDOLPH WEIDE, OF BERLIN, GERMANY, ASSIGNOR TO HERMANN HURWITZ & CO., OF BERLIN, GERMANY

APPARATUS FOR DISPLACING THE COUNTER PRESSURE ROLLER ON THE MISSING OF A SHEET IN MULTIPLE REPRODUCTION APPARATUS

Application filed September 9, 1929, Serial No. 391,418, and in Germany September 6, 1928.

In multiple reproduction apparatus in which the sheet to be printed is pressed by a counter pressure roller against the printing cylinder it may happen that on the missing of a sheet the counter pressure roller itself on the further rotation of the machine is inked by the printing cylinder and then smears the back of the next sheet. The invention relates to a device which, in the case of a sheet missing, automatically moves away the counter pressure cylinder. For this purpose, according to the invention, a feeler is provided which is controlled by the sheet to be applied so that on the missing of a sheet it can so move that an apparatus set in action thereby can move the counter pressure roller away on the further working of the machine. The drawings show as an example a method of carrying out the invention, and in this:

Fig. 1 shows the parts in question of a multiple printing plant, seen from the side, the side wall carrying the roller as also the deflecting apparatus, being omitted.

Fig. 2 is a section through Fig. 1 in the direction of the line 2—2. Here the side wall of the multiple printing plant carrying the apparatus is shown.

Fig. 3 is a side view of the part of the machine in question, and Fig. 4 is a section through Fig. 3.

In the drawings *a* is a feeler the end of which is curved in the shape of a circle and which is fixed on a shaft *b*. On the same shaft is provided a weight *b'* which tends to rotate the shaft counter clockwise. The feeler *a* fits in between two rollers *c* and *d*, which rollers have recesses at points lying opposite each other, which are indicated by the broken line circles in Fig. 1. The rollers *c* and *d* serve for the feeding of the paper sheet *B*. When a paper sheet is fed in the movement of the feeler upwards is limited by the paper sheet; the feeler then rests entirely in the recess of the roller *c*, while on the missing of a paper sheet it can swing out into the position shown on the drawings in which it projects above the contact plane of the two rollers *c* and *d* and forward into the recess of the roller *d*. On the shaft *b* is also

firmly fixed an arm *g*; this arm is connected by means of a link *h* with a double lever *i*, the bolt *i'* provided in one arm of the double lever *i* running in a slot *e* of the link *h*, and the lever arm *i* bears against a spring *f* arranged in the link so that any movement made by the double lever *i* is transmitted by spring action on to the arm *g* or conversely from the arm *g* on to the lever *i*. The free end of the lever *i* is formed as a nose piece *i'*. This nose piece co-operates with a projection *k*, which is fitted, for example, by means of the two screws *k'* on a rocking lever *l*. This rocking lever can swing freely about the shaft *b*. The rocking lever has an arc shaped slot *l'* by means of which it encloses the axle *s*, so that the rocking lever can move freely within a certain angle. A toothed segment *n* is also provided on the rocking lever which is fixed on the rocking lever for example by means of the screw *n'*. A curved double armed lever *p* rocking about a fixed axis *o* is rotatably connected at one end to the rocking point of the double lever *i*, while the second end bears, through an interposed spring *p'*, against a lever *p''*, which carries a roller *m*. The upper free lever arm of the double lever *p''* and the arm *p'* can be adjusted by means of the screw connection shown, together with the spring, in any desired manner, in order to regulate the position of the roller and therefore the commencement of the working period of the lever *p*. The roller *m* bears against a cam path *q* provided on the circumference of the pressure roller *D* and is controlled thereby.

The shaft *s* carries a toothed wheel *t* which engages with the toothed segment *n*. The centre part *v* of the shaft *s* is made eccentric. This eccentric part serves to carry the counter pressure roller *D*. On the rising or falling of the rocking lever *l* the shaft *s* is correspondingly rotated by means of the toothed wheel transmission and then in consequence of the rotation of the eccentric part *v* the counter pressure roller *D* is raised or lowered. To fix or hold the toothed wheel *t* and the shaft *s* in one or the other end positions, a disc *r* connected to the shaft is provided, this having two recesses in which alternately

the point of a spring pin α can enter. The upper roller d is carried in a frame w which oscillates about a journal y . The movement of the frame w takes place by means of a lever z which is rotatably connected at y' with the frame w by means of a stop screw z' which is adjustable with respect to the frame w , and bears by means of a roller z^2 on a cam disc q^2 , which again is connected with the printing cylinder D . The method of operation of the apparatus is as follows:

As long as a sheet to be printed is introduced between the sheet feed rollers c and d , the feeler α is pressed down, that is, it remains inside the recess of the roller c . Consequently the shaft b , contrary to the position shown in the drawings, is rotated slightly in the clockwise direction and for about an amount which is given by the second centre line shown. The lever g is rotated to the left by a corresponding amount which is shown by the second centre line; consequently the pawl i is swung out in the clockwise direction and its point takes up the position shown in the drawings by the dotted and broken line. On the further movement of the drum D the roller m runs up on the cam q . Consequently the lever p rotates in the clockwise direction; the pawl i is thus moved upwards; it can move freely on the outer side of the stop k , so that the working stroke can take place in the ordinary manner, that is, the paper sheet B supplied is carried forward through the rollers c and d , arrives between the pressing on roller and the printing drum and is printed.

In case a sheet B misses, then in consequence of the weight b' the feeler α will swing out in counter clockwise direction, that is, it will take up the position shown in the drawings. Consequently the pawl i moved by the lever g and the link h takes up the position shown in full or broken lines, in which it rests underneath the stop k . If now on the further rotation of the drum D the lever p is oscillated by means of the roller m and the cam q in the clockwise direction, then the lever i raises the stop k and with it the rocking lever l also. The consequence of this is that the toothed segment n fastened on the rocking lever carries with it the toothed wheel t and also the shaft s carrying the eccentric part v and the disc r . A rotation of about 90° takes place. The pin α is thus forced out of the groove in which it finds itself and engages in the other groove of the disc r . By the rotation of the eccentric part of the shaft s which carries the pressing on roller, the pressing on roller has been lowered by a certain amount. When now on the further rotation of the drum D the inked part of the printing drum comes opposite the counter pressure drum D^2 , the latter is situated too low for colour to be transmitted thereto.

The apparatus can, of course, be carried out

constructively in other ways, in particular other means may be used for the transmission of the movement as, for example, friction coupling or the like.

When the machine is to be again started, the shaft s must be rotated back into its initial position. This rotation backward takes place by holding the disc r by the hand and rotating it until the pin α again engages in the other groove and fixes the apparatus in the working position.

A further apparatus can be preferably combined with this arrangement, according to which during the working of the apparatus an adjustment of the pressure can take place. This apparatus is shown in Figs. 3 and 4. In so far as the parts in this figure correspond to Fig. 1 they are provided with the same reference signs.

In the construction according to Figs. 1 and 2 the adjustment of the counter pressure is regulated by the toothed wheel t being coupled through a claw coupling with axially directed claws with a disc r^1 which disc r^1 again is connected with the disc r by means of clamping screws r^0 which run in a slot of the disc r so that on loosening these clamping screws and adjusting the parts r and r^1 with respect to each other, the shaft s may be rotated with respect to the toothed wheel t and thus the eccentricity be adjusted. This could, of course, only take place when the machine is stopped. In order now to be able to effect this adjustment while running, the clamping screws r^0 are dispensed with and the parts are made in the manner shown in Figs. 3 and 4. Here, similarly to the usual form of construction, according to Figs. 3 and 4 the part r^2 corresponding to the part r of the first form of construction, is fitted by means of an extended slot opening on the flattened front end s' of the shaft s , so that by rotating this part r^2 the shaft s may be rotated, for example, to set it in again after it has been drawn back by the missing of a sheet. The disc r^2 is for this purpose provided with handles r^3 . The part coupling the disc r^2 with the toothed wheel t and which is indicated by r^4 in the construction according to Figs. 3 and 4, is now not firmly connected with the part r^2 but is made in the form of a worm wheel. The part r^2 has a projection r^5 serving as the bearing for a worm r^6 which is provided with a hand piece r^7 and engages in the worm wheel r^4 .

Consequently by the rotation of the head r^7 an adjustment of the parts r^2 and r^4 with respect to each other may be made, this being at any time possible while the machine is working. By means of this rotation of the two parts with respect to each other, the shaft s is rotated and thus the eccentric part v of this shaft is brought more or less close to the pressure roller or moved away from it and thus the pressure with which the counter pressure roller bears against the printing roll.

er is increased or diminished. The disc r^2 may be suitably provided at its upper end with a recess having a mark r^8 thereon and behind which a scale r^9 on the part r^4 , appears, so that the position at the moment of the two parts with respect to each other may be read off.

I claim:

1. Apparatus for displacing the counter-pressure roller on the missing of a sheet in multiple reproduction apparatus comprising, in combination, with a counter-pressure roller and the printing drum, a stop piece, a curved disc connected with the printing drum and continuously moving said stop piece to and fro, a stop adapted to be engaged by said stop piece, a gearing adapted to displace the counter-pressure roller and controlled by said stop, and a feeler controlled by the sheet to be fed and controlling said stop piece so as to engage said stop and moving it for displacing the counter-pressure roller, if no sheet is fed.
2. Apparatus according to claim 1, in which the gearing consists of a rocking lever and a toothed gearing rotated by said rocking lever when moved by said stop, said toothed gearing being coupled with the counter-pressure roller, the rotary axis of which is eccentrically shaped.
3. Apparatus according to claim 1, in which the gearing consists of a rocking lever and a toothed gearing rotated by said rocking lever when moved by said stop, said toothed gearing being coupled with the counter-pressure roller, the rotary axis of said counter-pressure roller being eccentrically shaped and having attached thereto a disc with recesses and being combined with a spring pin engaging said recesses in two end positions of the counter roller.
4. Apparatus according to claim 1, in which the gearing consists of a rocking lever and a toothed gearing rotated by said rocking lever when moved by said stop, said toothed gearing being coupled with the counter-pressure roller, the rotary axis of said counter-pressure roller being eccentrically shaped and having attached thereto a disc with recesses and being combined with a spring pin engaging said recesses in two end positions of the counter roller, said counter roller being provided with a disc and being combined with a coupling gearing capable of being adjusted while running, said coupling gearing being connected with the disc by means of a coupling part connected with said coupling gearing.

In testimony whereof I affix my signature.
RUDOLPH WEIDE.
